UNITED STATES PATENT OFFICE

GEORGE THOMAS, OF RAHWAY, NEW JERSEY

SAFETY DEVICE FOR GAS BURNERS AND THE LIKE

Application filed July 6, 1929. Serial No. 376,388.

My invention relates to safety devices for gas burners and the like and it consists in the constructions, arrangements and combinations herein described and claimed.

8 It is an object of my invention to provide a safety device of such construction as to prevent accidental opening of the valve.

16 It is a further object of my invention to provide a safety device wherein the detent means functions as a retaining means for the valve.

15 A still further object of my invention is to provide a safety device of simple construction, and one which will be liable in a minimum degree to derangement.

20 Additional objects, advantages and features of invention will be apparent from the following description and accompanying drawings, wherein,

Figure 1 is a top plan view of my invention applied to the valve of a gas stove burner,

Figure 2 is a side elevation thereof,

25 Figure 3 is an end view thereof,

Figure 4 is a cross section on the line 4—4 of Fig. 3,

Figure 5 is a cross section on the line 5—5 of Fig. 3,

30 Figure 6 is a plan view of the combined valve handle and catch,

Figure 7 is a perspective view of the valve and valve handle retaining spring,

Figure 8 is a modified form of retaining

35 spring.

In carrying out my invention I provide a gas burner, which may be of any usual construction having a valve 2. The valve 2 in the present instance, is illustrated as 40 the usual plug valve type having a handle 3 extending at right angles to the plug body 4.

The handle 3 is secured upon a shank 5 which is rigidly fixed in the upper portion 45 6 of the plug 4. From a consideration of Figures 1, 2 and 3, it will be seen that the shank 5 extends through the portion 6 of the valve, and is curved downwardly and rearwardly, as at 7, so as to lie in a plane 50 substantially parallel to the handle 3, where

it is recurved as at 8, to provide a loop 9. The terminal of the shank 5 is preferably curved outwardly as at 10. The formation of the handle shank 5 in this manner provides a locking means, for a purpose which 55 will be apparent, as the description proceeds.

The valve 2 has an inlet 11 suitably connected to a gas manifold 12, and an outlet pipe 13 connected to the burner 1, as customary.

Upon the outlet pipe 13, there is provided a plate 14 which as shown, is apertured and suitably secured to the pipe 13 as by welding. This plate 14 is positioned 60 closely adjacent the valve 2, and has at its lower portion a lateral arm 15. The upper edge of the plate 14 is recessed as at 16, and a slot 17 is provided intermediate the length of the plate, this slot being in the path of 70 movement of the portion 10 of the shank 5.

The lower portion of the valve plug 4 has an annular recess 18 immediately outward of the valve body 2, to receive a retaining clip as will now be described.

A combined valve and valve retaining spring 19 is mounted upon the arm 15 of the plate 14, this spring in the present instance, being formed from a single strand of wire. Attention is directed to Figures 3 and 7 80 wherein it will be seen that the spring 19 is formed intermediate its length with a helix 20 of a size to snugly engage the arm 15, as shown, with extended portions 21 and 22. The portion 21 is bent at right angles 80 to the helix 20 and terminates in a clip member 23. The clip 23 is engaged within the annular groove 18 of the plug 4 and retains the valve plug 4 securely seated within the valve body, as clearly shown in Figures 2, 3 and 5. The portion 22 of the spring 19 is of a length to extend beyond the upper edge of the plate 14, a distance, where it is bent to form a loop 24, and is continued 90 downwardly so as to cross the portion 22. The portion 22 terminates in a hook 25 adapted to engage the upper edge of the plate by virtue of its extension through the recess 16. Normally, the portion 22 extends 95 between the loop 24 and the plate 14, and

100

by virtue of the resilience of the spring 19, the member 22 tends to bear upon the inner side of the loop 9 and thus hold the handle 3 and associated parts against accidental movement.

With the parts in the positions shown in Figures 1, 2 and 3, in order to turn the valve plug 4, the handle 3 is grasped, and at the same time, the loop 24 is pushed inwardly and forwardly toward the open end of the loop 8. At this time, the handle 3 is swung as indicated by the arrow in Figure 1. Such movement will swing the end 10 through the slot 17 and free the member 22 so that it may spring back to its normal position, shown in Fig. 3. Upon reverse movement of the handle 3, the loop 24 is again pushed inwardly and forwardly toward the open end of the loop 8, which will permit the end 10 to swing through the slot 17 in position to receive the member 22 when released. With return of the member 22 to a position within the loop 8, it will be apparent that the end 10 will be latched against accidental movement.

In Figure 8, I have shown a modified form of retaining spring, in which the member 22^a terminates in a loop 24^a having a bill 25^a arranged to engage a stop lug 30. Also, the member 22^a is reinforced as at 31 to compensate for wear which may occur between it and the member 10.

From the foregoing it will be apparent that I have provided a safety device of extremely simple construction, and one which also provides means for effectively retaining the valve in its engaged relation with the valve body.

I claim:

1. A safety device for gas valves or the like comprising a valve body, a valve therein having a handle, a recurved extension carried upon one end of said handle and movable therewith, a plate carried by said valve having a slot in the path of movement of said extension adapted to receive said extension in one movement of the handle, and a resilient spring disposed between said plate and said extension to latch said valve against accidental movement.

2. A safety device for valves comprising a valve body, a rotatable valve therein, a handle for said valve having an extension rearwardly curved and terminating in a hook, a plate mounted upon said valve having a slot adapted to receive said hook upon rotation of said valve in one direction, and a resilient spring disposed between said hook and said plate to latch said valve against accidental movement.

3. A safety device for valves comprising a valve body, a rotatable valve therein, a handle for said valve having an extension rearwardly curved and terminating in a hook, a plate adjacent said valve having a

slot adapted to receive said hook upon rotation of said valve in one direction, and a resilient spring disposed between said hook and said plate to latch said valve against accidental movement, said spring extending above said plate and into close proximity of said handle to provide an operating means for releasing said hook member. 70

4. A safety device for gas valves or the like comprising a valve body, a rotatable valve therein having a latching member, and retaining means for said valve having an extension projected into the path of said locking member to be engaged thereby to latch said valve against accidental movement. 75

5. A safety device for gas valves or the like comprising a valve body, a plug valve therein having a latching member, means for rotating said valve, retaining means upon the lower end of said valve having a resilient extension projected into the path of said locking member to be engaged thereby to hold said valve in position, and means upon said extension for releasing said latching member. 80

GEORGE THOMAS.
